SAMUEL DUNCAN BLACK AND ALONZO G. DECKER, OF TOWSON, MARYLAND,
ASSIGNORS, BY MESNE ASSIGNMENTS, TO SECOND NATIONAL BANK OF
BALTIMORE, TRUSTEE, OF BALTIMORE, MARYLAND.

DESIGN FOR A PORTABLE ELECTRIC TOOL.

57,576.

Specification for Design.

Patented Apr. 26, 1921.

Application filed May 17, 1920. Serial No. 382,170. Term of patent 14 years.

To all whom it may concern:

Be it known that we, SAMUEL DUNCAN BLACK and ALONZO G. DECKER, citizens of the United States of America, and residents of Towson, county of Baltimore, State of Maryland, have invented a new, original, and ornamental Design for a Portable Electric Tool, of which the following is a specification.

In the accompanying drawing we have illustrated a portable electric tool, or casing therefor, constructed in accordance with our invention.

The figure is a perspective view of the same.

The device as seen consists of a hexagonal motor casing, 1, a gear casing, 2, a tool chuck, 6, a switch-box, 3, a grip, 4, re-

sembling in form a pistol grip, and a controlling switch, 5, adjacent the pistol grip, having the configuration of and being arranged in the relation to the grip usually borne by the trigger of a pistol to the grip of the pistol.

Having thus described and illustrated our invention, we claim:

The ornamental design for a portable electric tool, substantially as shown and described.

Signed by us at Towson, Maryland, this 6th day of May, 1920.

SAMUEL DUNCAN BLACK.
ALONZO G. DECKER.
